HYDRAULIC DRIVE

Ransom Tyler, Greenfield, Wis., assignor to The Oilgear Company, Milwaukee, Wis., a corporation of Wisconsin

Application August 15, 1942, Serial No. 454,962

13 Claims. (Cl. 60—53)

This invention relates to hydraulic drives of the type employed to drive a plurality of shafts or machine elements the speeds of which should be maintained at an exact ratio.

Various drives of this type have heretofore been provided some of which function satisfactorily when the drive is operating at or near its normal speed but which fail to maintain the desired ratio between the speeds of the shaft or elements during starting and stopping of the drive.

The primary object of the present invention is to provide a hydraulic drive capable of driving a plurality of shafts or elements at a desired ratio and maintaining that ratio substantially constant throughout the entire range of speeds between zero and maximum.

Other objects and advantages will appear from the following description of a drive constructed according to the invention and shown schematically in the accompanying drawing in which the views are as follows:

Fig. 1 is a circuit diagram of a drive embodying the invention.

Fig. 2 is a view showing the start and stop valve in a position different from that shown in Fig. 1.

For the purpose of illustration, the invention has been shown embodied in a drive adapted to drive, for example, a wire forming machine of which, since it forms no part of the present invention, only the drive shaft 1 of the feeding section and the drive shaft 2 of the forming section have been shown. The feeding section feeds a continuous strand or strands of wire to the forming section which cuts the wire into pieces of equal length and forms the pieces into articles of desired shapes. The speeds of the two sections must be kept proportional to each other as otherwise the pieces cut from the wire would vary in length and be too long or too short to form finished articles of the desired shapes.

Shaft 1 is driven by a hydraulic transmission comprising a motor 3 and a pump 4, and shaft 2 is driven by a hydraulic transmission comprising a motor 5 and a pump 6. Motor 3 has its shaft 7 mechanically connected to shaft 1, as by means of a coupling 8, and it is hydraulically connected to pump 4 by channels 9 and 10. Motor 5 has its shaft 11 mechanically connected to shaft 2, as by means of a coupling 12, and it is hydraulically connected to pump 6 by channels 13 and 14. Each of the pumps is driven at a substantially constant speed by power derived from a suitable power source such as an electric motor not shown.

Pump 6 may be of any suitable type but it has been shown as being of the type illustrated and

described in Patent No. 2,074,068. It is deemed sufficient to state herein that its pumping mechanism is arranged within a displacement varying member or slide block 15 and that it will deliver liquid to motor 5 at a rate determined by the distance slide block 15 is offset from its neutral position, the displacement and delivery of pump 6 being zero when slide block 15 is in neutral position.

Slide block 15 is constantly urged toward neutral position by low pressure liquid acting upon a servo-motor piston 16 which is connected to or abuts slide block 15 and is fitted in a cylinder 17 fixed to the casing of pump 6. Slide block 15 is adapted to be moved toward the right away from its neutral position by liquid at a higher pressure acting upon a servo-motor piston 18 which is connected to or abuts slide block 15 and is fitted in a cylinder 19 fixed to the casing of pump 6.

Pump 4 may be of the same general construction as pump 6 and it is preferably of the variable displacement type. As shown, its slide block 20 is adapted to be shifted by a manually operable screw 21 which may be rotated to vary the displacement of pump 4 and thereby vary the overall speed of the machine. Motors 3 and 5 may be of the same general construction as pump 6 but they are ordinarily of the constant displacement type.

Motor 5 is started and stopped by shifting slide block 15 of pump 6 from and to its neutral position. Motor 3 is started and stopped by means of a valve 25 arranged in a valve casing 26 which is connected intermediate its ends by channels 27 and 28 to opposite sides of pump 4 and has its ends connected to drain as by being connected to a reservoir 29 arranged beneath the casing of pump 4. Valve 25 controls communication between channels 27 and 28 and between channel 27 and a channel 30 into which liquid from pump 4 is directed for a purpose to be presently explained.

Liquid for energizing servo-motor 16—17 may be supplied thereto from any suitable low pressure source such as a gear pump 31 which has been shown separate from pump 4 but which in practice is driven in unison with pump 4 and arranged in the casing thereof in the customary manner and as shown in Patent 2,074,068. Gear pump 31 draws liquid from reservoir 29 and discharges it into a channel 32 which is connected to cylinder 17. The liquid discharged by gear pump 31 in excess of requirements is exhausted into reservoir 29 through a low pressure relief valve 33 which enables gear pump 31 to maintain in channel 32 and in cylinder 17 a constant low

pressure proportional to the resistance of relief valve 33.

Liquid for energizing servo-motor 18-19 when the machine is running is supplied thereto in response to a variation in the relative speeds of two small pumps or meters 36 and 37 which are driven in synchronism with motors 3 and 5 respectively. As shown, meter 36 has its shaft connected to the shaft 7 of motor 3 by a drive 38 and meter 37 has its shaft connected to the shaft 11 of motor 5 by a drive 39.

Meters 36 and 37 are connected together into a closed circuit by means of a channel 40, which connects the inlet of meter 36 to the outlet of meter 37, and a channel 41 which connects the outlet of meter 36 to the inlet of meter 37 and which is also connected by a channel 42 to cylinder 19. In order to keep the circuit completely filled with liquid, channel 40 is connected to gear pump channel 32 by a channel 43 and channel 41 is connected to gear pump channel 32 by a channel 44 having arranged therein a check valve 45 which permits liquid to flow from channel 32 into channel 41 but prevents liquid from flowing from channel 41 into channel 32.

The function of meters 36 and 37 is to maintain the speed of motor 5 proportional to the speed of motor 3. The ratio between the speeds of motors 3 and 5 is determined by the relative displacements of meters 36 and 37 and by the speeds at which the meters are driven.

In order that the ratio between the speeds of motors 3 and 5 may be readily varied, one or both of the motors may be provided with means for varying its displacement. As shown, meter 36 is provided with a hand wheel 46 for varying its displacement. For example, meter 36 may be of the same type as pump 4 and have its displacement varied in substantially the same manner.

Meters 36 and 37 are capable of maintaining the speed of motor 5 proportional to the speed of motor 3 during normal operation of the drive but they are incapable of causing motor 5 to start simultaneously with motor 3 or to decelerate to a stop synchronously with motor 3.

In order that motor 5 may be started and stopped synchronously with motor 3, a metered volume of liquid is supplied to or permitted to escape from cylinder 19 in response to operation of start and stop valve 25. This is accomplished by means of a metering device comprising a cylinder 51 and a piston 52 fitted therein. The device may also include an adjusting screw 53 for limiting the stroke of piston 52 to thereby regulate the volume of liquid supplied to or permitted to escape from cylinder 19.

Cylinder 51 has channel 30 connected to one of its ends and a channel 54 connected to its other end. Channel 54 is connected to channel 42 through two oppositely opening check valves 55 and 56, which are arranged in parallel with each other, a throttle valve 57 which is connected in series with check valve 55 and a throttle valve 58 which is connected in series with check valve 56.

Operation

With the parts in the positions shown and the pumps running, the liquid discharged by pump 4 flows through channel 27, valve casing 26 and channel 28 back to the intake of pump 4 so that motor 3 is idle, gear pump 31 is drawing liquid from reservoir 29 and discharging it through relief valve 33 back into reservoir 29. The pressure created by gear pump 31 extends through

channels 32 and 42 and acts upon pistons 16 and 18. Since piston 18 is larger than piston 16, it holds pump 6 at zero stroke so that motor 5 is idle. Gear pump pressure also extends from channel 42 through valves 58 and 56 and channel 54 to cylinder 51 and holds piston 52 against the left end of cylinder 51 as shown.

When valve 25 is shifted from the position shown in Fig. 1 to the position shown in Fig. 2, liquid discharged by pump 4 will flow through channel 9 to motor 3 to energize it and at the same time liquid will flow from pump 4 through channel 27, valve casing 26 and channel 30 to cylinder 51 and cause piston 52 to move toward the right and expel a predetermined volume of liquid from cylinder 51 through channel 54, check valve 55 and throttle valve 57 into channel 42 and cylinder 19.

Since this predetermined volume of liquid cannot escape from channel 42 into the gear pump circuit due to check valve 45 and since piston 18 is being held in its zero displacement position by gear pump pressure acting upon piston 16 the area of which is somewhat larger than the area of piston 18, piston 52 will create in channel 42 and in cylinder 19 a pressure of a low value but enough higher than gear pump pressure to enable piston 18 to shift slide block 15 toward the right to cause pump 6 to deliver liquid through channel 13 to motor 5 to energize it. Motors 3 and 5 are thus started simultaneously.

The volume of liquid expelled from cylinder 51 into cylinder 19 is just sufficient to enable piston 18 to shift slide block 15 far enough to enable pump 6 to discharge liquid at the rate required to drive motor 5 at a predetermined speed such as its normal running speed. If the flow from cylinder 51 to cylinder 19 were unrestricted, the volumetric delivery of pump 6 would be almost instantly increased to the predetermined value and motor 5 would be accelerated at an uncontrolled rate which might be too great to maintain the speeds of motors 3 and 5 at the preset ratio but the flow to cylinder 19 is restricted by throttle valve 57 which may be adjusted to regulate the rate at which the displacement of pump 6 is increased and thereby regulate the rate at which motor 5 is accelerated.

As soon as motors 3 and 5 start to operate, meters 36 and 37 start to operate in unison therewith respectively. If motor 5 and meter 37 should run too slow relative to the speeds of motor 3 and meter 36 or if the speed of meter 36 should be increased as by increasing the displacement of pump 4 and thereby increasing the speed of motor 3, the volume of liquid discharged by meter 36 into channel 41 would be in excess of the volume drawn therefrom by meter 37 and the excess liquid would flow through channel 42 to cylinder 19 and cause piston 18 to increase the displacement of pump 6 and thereby increase the speeds of motor 5 and meter 37 until the speeds of motors 3 and 5 were at the preset ratio and then the intake rate of meter 37 would exactly equal the output rate of meter 36 and further adjustment of pump 6 would cease.

If the speed of motor 5 should increase relative to the speed of motor 3 or if the speed of motor 3 should be decreased, the relative speeds of meters 36 and 37 would vary accordingly. The volume of liquid discharged by meter 37 into channel 40 would be in excess of the volume drawn therefrom by meter 36 and the excess liquid would be expelled through channel 43 and relief valve 33 into reservoir 29. The volume of liquid dis-

charged by meter 36 into channel 41 would be less than the volume drawn therefrom by meter 37 and enough liquid to make up this deficiency would be drawn by meter 37 from cylinder 19 for the reason that, since piston 16 is constantly subjected to gear pump pressure and is larger than piston 18, the force exerted by piston 16 causes piston 18 to maintain in channels 42 and 41 a pressure which is higher than gear pump pressure and holds check valve 45 closed so that gear pump 31 cannot at this time supply liquid to meter 37. The liquid drawn from cylinder 19 by meter 37 would enable the gear pump pressure in cylinder 17 to cause piston 16 to move slide block 15 toward the left to decrease the speeds of motor 5 and meter 37 until the speeds of motors 3 and 5 were at the preset ratio and then the intake rate of meter 37 would exactly equal the output rate of meter 36 and further adjustment of pump 6 would cease.

When valve 25 is shifted to the position shown in Fig. 1 to bypass pump 4 as previously explained, motor 3 will coast to a stop. Shifting valve 25 will also connect channel 30 to drain and enable the liquid supplied to cylinder 17 by gear pump 31 to cause piston 16 to shift slide block 15 toward the left and the liquid expelled from cylinder 19 by piston 18 during movement of slide block 15 toward the left will flow through channel 42, throttle valve 58, check valve 56 and channel 54 to cylinder 51 and move piston 52 toward its neutral position.

If the flow from cylinder 19 were unrestricted, the displacement of pump 6 would be reduced to zero almost instantly and the liquid discharged by motor 5 would be forced through the high pressure relief valve of pump 6, thereby imposing a high brake load upon motor 5 and causing it to decelerate faster than motor 3. However, throttle valve 58 is adjusted to so regulate the rate of discharge from cylinder 19 that the rate of deceleration of motor 5 is maintained proportional to the rate of deceleration of motor 3, meters 36 and 37 continuing to control at least in part the speed of motor 5 relative to the speed of motor 3 during deceleration of the motors.

If when valve 25 is shifted slide block 15 is located at or toward the left from the position to which it was initially moved in response to operation of piston 52, it will be returned to neutral in response to operation of valve 25 but if at that time it is located at the right of that position, operation of valve 25 will cause piston 16 to move slide block 15 toward the left until the liquid ejected from cylinder 19 by piston 18 has fully retracted piston 52 and thereafter piston 16 will move slide block 15 farther toward the left to its neutral position in response to meter 37 drawing liquid from cylinder 19 due to meter 36 decelerating faster than meter 37.

If the volume of liquid delivered to cylinder 51 from cylinder 19 is insufficient to move piston 52 fully to its initial position, liquid from gear pump 31 will flow through channel 32, check valve 45, channels 44, 41 and 42, throttle valve 58, check valve 56 and channel 54 to cylinder 51 and move piston 52 fully to its initial position.

While the invention has been shown embodied in a drive comprising a master transmission for driving one shaft or machine, a follower transmission for driving a second shaft or machine and controls for maintaining the speeds of the shafts or machines at a given ratio, it will be obvious that the invention may be adapted to drive a larger number of shafts or machines by

simply adding additional follower transmission and controls therefor and that the drive is susceptible of various other modifications and adaptations without departing from the scope of the invention which is hereby claimed as follows:

5. 1. In a hydraulic drive having a first hydraulic motor, a first pump connected to said motor to energize the same, a second hydraulic motor, a second pump connected to said second motor to energize the same and provided with a hydraulically operated control for varying its displacement, the combination of means responsive to a variation in the relative speeds of said motors for effecting operation of said pump control to thereby correct such speed variation, means for starting said first motor, and means independent of said speed responsive means and responsive to operation of said starting means for effecting operation of said pump control to thereby cause said second motor to start substantially simultaneously with said first motor.
10. 2. In a hydraulic drive having a first hydraulic motor, a first pump connected to said motor to energize the same, a second hydraulic motor, a second pump connected to said second motor to energize the same and provided with a hydraulically operated control for varying its displacement, the combination of means for controlling the flow of liquid from said first pump to said first motor, and means for causing a predetermined quantity of liquid to flow to said pump control and thereby effect a definite adjustment of the displacement of said second pump in response to operation of said flow control means.
15. 3. In a hydraulic drive having a first hydraulic motor, a first pump connected to said motor to energize the same, a second hydraulic motor, a second pump connected to said second motor to energize the same and provided with a hydraulically operated control for varying its displacement, the combination of means for controlling the flow of liquid from said first pump to said first motor, means responsive to operation of said flow control means for causing a predetermined quantity of liquid to flow to or from said pump control and thereby effect a variation in the displacement of said second pump, and means for regulating the rate of flow of said definite volume of liquid to thereby regulate the
20. 4. In a hydraulic drive having a first hydraulic motor, a first pump connected to said motor to energize the same, a second hydraulic motor, a second pump connected to said second motor to energize the same and provided with a hydraulically operated control for varying its displacement, the combination of means for controlling the flow of liquid from said first pump to said first motor, means responsive to operation of said flow control means for causing a predetermined quantity of liquid to flow to or from said pump control and thereby effect a variation in the displacement of said second pump, and two oppositely opening check valves connected between said last mentioned means and said pump control in parallel with each other and a choke connected in series with each check valve to regulate the rate at which said definite volume of liquid may flow to or from said pump control.
25. 5. In a hydraulic drive having a first hydraulic motor, a first pump connected to said motor to energize the same, a second hydraulic motor, a second pump connected to said second motor to energize the same and provided with a hy-

draulically operated control for varying its displacement, the combination of means responsive to a variation in the relative speeds of said motors for effecting operation of said pump control to thereby correct such speed variation, a metering device independent of said speed responsive means for directing a definite volume of liquid to and for receiving said definite volume of liquid from said pump control, and a valve for controlling said first motor and said metering device to effect simultaneous operation thereof.

6. In a hydraulic drive having a first hydraulic motor, a first pump connected to said motor to energize the same, a second hydraulic motor, a second pump connected to said second motor to energize the same and provided with a hydraulically operated control for varying its displacement, the combination of means responsive to a variation in the relative speeds of said motors for effecting operation of said pump control to thereby correct such speed variation, a metering device for directing a definite volume of liquid to and for receiving said definite volume of liquid from said pump control, a valve for controlling said first motor and said metering device to effect simultaneous operation thereof, and means for regulating the rate of flow of said definite volume of liquid in each direction independently of its rate of flow in the opposite direction.

7. In a hydraulic drive having a first hydraulic motor, a first pump connected to said motor to energize the same, a second hydraulic motor, a second pump connected to said second motor to energize the same and provided with a hydraulically operated control for varying its displacement, the combination of a valve for controlling the flow of liquid from said first pump to said first motor, a cylinder having one end connected to said pump control and its other end connected to said valve, and a piston in said cylinder adapted when energized to eject a definite volume of liquid from said cylinder to said pump control, said valve being shiftable to two positions in one of which it causes liquid to flow from said first pump to said first motor and to said cylinder and in the other of which it bypasses said first pump and connects said cylinder to exhaust.

8. In a hydraulic drive having a first hydraulic motor, a first pump connected to said motor to energize the same, a second hydraulic motor, a second pump connected to said second motor to energize the same and provided with a hydraulically operated control for varying its displacement, the combination of a valve for controlling the flow of liquid from said first pump to said first motor, a cylinder having a first end thereof connected to said pump control and the second end thereof connected to said valve, a piston in said cylinder adapted when energized to eject a definite volume of liquid from said cylinder to said pump control, said valve being shiftable to two positions in one of which it causes liquid to flow from said first pump to said first motor and to the second end of said cylinder and in the other of which it bypasses said first pump and connects the second end of said cylinder to exhaust, and means for supplying liquid to the first end of said cylinder to completely fill the same and to urge said piston against the second end of said cylinder during the time said piston is deenergized.

9. In a hydraulic drive having a first hydraulic motor, a first pump connected to said motor to energize the same, a second hydraulic motor, a

second pump connected to said second motor to energize the same and provided with a hydraulically operated control for varying its displacement, the combination of a fluid meter driven in unison with each of said motors, fluid channels connecting said meters to each other and forming therewith a closed hydraulic circuit completely filled with liquid, a channel connecting one side of said circuit to said pump control so that a variation in the relative speeds of said meters will effect a flow of liquid to or from said pump control and cause the same to vary the displacement of said second pump, means for starting said first motor, and additional means responsive to operation of said starting means for effecting operation of said pump control to thereby cause said second motor to start substantially simultaneously with said first motor.

10. In a hydraulic drive having a first hydraulic motor, a first pump connected to said motor to energize the same, a second hydraulic motor, a second pump connected to said second motor to energize the same and provided with a hydraulically operated control for varying its displacement, the combination of a fluid meter driven in unison with each of said motors, fluid channels connecting said meters to each other and forming therewith a closed hydraulic circuit completely filled with liquid, a channel connecting one side of said circuit to said pump control so that a variation in the relative speeds of said meters will effect a flow of liquid to or from said pump control and cause the same to vary the displacement of said second pump, means for controlling the flow of liquid from said first pump to said first motor, additional means responsive to operation of said flow control means for causing a definite volume of liquid to flow to or from said pump control and thereby effect a variation in the displacement of said second pump, and means for regulating the rate of flow of said definite volume of liquid to thereby regulate the rate at which the displacement of said second pump is varied.

11. In a hydraulic drive having a first hydraulic motor, a first pump connected to said motor to energize the same, a second hydraulic motor, a second pump connected to said second motor to energize the same and provided with a hydraulically operated control for varying its displacement, the combination of a fluid meter driven in unison with each of said motors, fluid channels connecting said meters to each other and forming therewith a closed hydraulic circuit completely filled with liquid, a channel connecting one side of said circuit to said pump control so that a variation in the relative speeds of said meters will effect a flow of liquid to or from said pump control and cause the same to vary the displacement of said second pump, a metering device for directing a definite volume of liquid to and for receiving said definite volume of liquid from said pump control, and a valve for controlling said first motor and said metering device to effect simultaneous operation thereof.

12. In a hydraulic drive having a first hydraulic motor, a first pump connected to said motor to energize the same, a second hydraulic motor, a second pump connected to said second motor to energize the same and provided with a hydraulically operated control for varying its displacement, the combination of a fluid meter driven in unison with each of said motors, fluid channels connecting said meters to each other and forming therewith a closed hydraulic circuit

completely filled with liquid, a channel connecting one side of said circuit to said pump control so that a variation in the relative speeds of said meters will effect a flow of liquid to or from said pump control and cause the same to vary the displacement of said second pump, a metering device for directing a definite volume of liquid to and for receiving said definite volume of liquid from said pump control, a valve for controlling said first motor and said metering device to effect simultaneous operation thereof, and means for regulating the rate of flow of said definite volume of liquid in each direction independently of its rate of flow in the opposite direction.

13. In a hydraulic drive having a first hydraulic motor, a first pump connected to said motor to energize the same, a second hydraulic motor, a second pump connected to said second motor to energize the same and provided with a hydraulically operated control for varying its displacement, the combination of a fluid meter driven in unison with each of said motors, fluid channels connecting said meters to each other and forming therewith a closed hydraulic circuit completely filled with liquid, a channel connect-

5 ing one side of said circuit to said pump control so that a variation in the relative speeds of said meters will effect a flow of liquid to or from said pump control and cause the same to vary the displacement of said second pump, a valve for controlling the flow of liquid from said first pump to said first motor, a cylinder having a first end thereof connected to said pump control and the second end thereof connected to said valve, a piston in said cylinder adapted when energized to eject a definite volume of liquid from said cylinder to said pump control, said valve being shiftable to two positions in one of which it causes liquid to flow from said first pump to said first motor and to the second end of said cylinder and in the other of which it bypasses said first pump and connects the second end of said cylinder to exhaust, and means for supplying liquid to the first end of said cylinder to completely fill the same and to urge said piston against the second end of said cylinder during the time said piston is de-energized.

RANSOM TYLER.
